UNITED STATES PATENT OFFICE.

CEPHAS WHITNEY AND ALFRED CONSTANTINE LAZARUS, OF KINGSTON,
JAMAICA.

BICYCLE-GEAR.

SPECIFICATION forming part of Letters Patent No. 621,883, dated March 28, 1899.

Application filed October 16, 1896. Serial No. 609,090. (No model.)

To all whom it may concern:

Be it known that we, CEPHAS WHITNEY and ALFRED CONSTANTINE LAZARUS, residing at Kingston, Jamaica, have invented a new and Improved Bicycle-Gear, of which the following is a full, clear, and exact description.

The object of the invention is to provide a new and improved bicycle-gear which is simple and durable in construction and arranged in such a manner that the pedal and crank-hanger constantly change during each revolution to keep the thrust exerted by the rider on the pedal approximately at right angles, so as to insure a full utilization of the power exerted.

The invention consists of certain parts and details and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a side elevation of the improvement. Fig. 2 is an end elevation of the same. Fig. 3 is a side elevation of a modified form of the improvement. Fig. 4 is an end elevation of the same. Fig. 5 is an enlarged side elevation of part of the cam-race, the crank, and pedal. Fig. 6 is a transverse section of the same on the line 6 6 of Fig. 5. Fig 7 is a face view of a modified form of cam and link. Fig. 8 is a transverse section of the same on the line 8 8 of Fig. 7. Fig. 9 is a sectional plan view of a modified form of the same. Fig. 10 is a side elevation, with parts broken out, of a modified form of the improvement. Fig. 11 is an end view of the same with parts in section. Fig. 12 is a side elevation of another modified form of the improvement. Fig. 13 is an end view of the same. Fig. 14 is a cross-section of part of the same on the line 14 14 of Fig. 12; and Fig. 15 is an enlarged sectional plan view of one of the crank-arms on the line 15 15 of Fig. 12.

In the crank hanger or bracket A of the bicycle-frame, as shown in Figs. 1 and 2, is mounted to turn a crank-shaft B, carrying at its ends the cranks C, extending in opposite directions in the usual manner. On the outer end of each crank C is mounted a shaft

or pivot-pin D, supporting a pedal E near one end thereof, as plainly shown in the drawings, the said pedal being provided near its outer end with a roller F, adapted to engage a cam-race G, secured by suitable brackets G² to the front lower brace A² and arms A⁴ A⁵ A⁶, extending from the said brace A², the rear lower brace A³ and the center brace A', respectively, as plainly indicated in the drawings. The two cam-races G for the two pedals are also connected with each other by suitable stay-rods G³.

On the upper end of the cam-race G is secured or formed an inwardly and downwardly extending spring G', adapted to be engaged by the roller F at the time the pedal C is in an uppermost position, so that the pedal stands horizontally, or approximately so. When the rider exerts a downward and forward pressure on the pedal E, then the roller F cushions on the spring G' and travels up the same, while the crank C travels in the direction of the arrow a'. When the roller F nears the uppermost end of the spring G', then the pedal E has swung upward relatively to the crank C, and the pedal is now locked to the said crank C to form an extension therefor, the said pedal being for this purpose provided with a hook H, adapted to engage a lug C', formed on an extension C², projecting outwardly from the front end of the crank C. The hook H is fulcrumed at H', at or near the middle of the pedal E, and is pressed on by a spring, so as to hold the hook in engagement with the lug C'. During the further movement of the crank C the roller F travels down the segmental part of the race G, but not in contact, because of the rising at G⁴, and when the roller F finally leaves the lever end of the segmental part of the race it enters the race G⁵, which causes another swinging of the pedal E in an outward direction relatively to the crank, so as to move the hook H into engagement with the lug C³, formed on the extension C², the lug C³ standing approximately at right angles to the lug C'.

The pedal E now stands again at angles to the crank C, and during the movement of the roller F in the last or lower part of the cam-race G remains in this position, but not in contact with the cam-race, until it comes again in con-

tact with the same at G' and owing to the rising at the beginning of the last or lower part of the cam-race. When the crank C finally swings upward on the return stroke, then the 5 pedal is pushed forward again to finally assume the position in Fig. 1 at the time the crank C is in an uppermost position. The free end of the spring G' is adapted to engage buffers G⁷ G⁸ to relieve the pedal E of 10 sudden shocks and jars.

In the arrangement illustrated in Figs. 3 to 9, inclusive, the crank-shaft B' carries on each end a crank C⁴, in the free end of which is journaled by a suitable ball-bearing a 15 transversely-extending shaft D', on which is fastened the pedal E' by means of suitable set-screws E². (See Figs. 5 and 6.) On the inner end of the shaft D' is secured an arm I, pivotally connected by a ball-bearing with 20 a link J, carrying at its free end a roller F', mounted to travel in a cam-race G⁹, supported from the frame parts of the bicycle-frame A¹. The roller F' is of the ball-bearing kind, the ball-bearing being of a suitable construction, such as indicated in Figs. 6, 7, 8, and 9.

Now it will be seen that when the rider engages the pedal E' and presses the same the said pedal is controlled in its motion from the cam-race G⁹ by the roller F' and the link J, 30 acting on the arm I, secured to the shaft D', on which the pedal is securely fastened. Thus the pedal E' will form an extension to the crank C⁴ during the downstroke of the crank C⁴, so that the power exerted by the 35 rider is utilized through the downstroke of the said crank.

In the modified form shown in Figs. 10 and 11 the crank-shaft B² carries the cranks C⁵, each of which is provided in its outer end 40 with a transversely-extending shaft D², supporting an arm D³, on which the pedal E³ is journaled. The inner end of the shaft D² carries a gear-wheel K in mesh with an intermediate gear-wheel K', mounted to turn on 45 a stud held on the crank C⁵. The intermediate gear-wheel K' is in mesh with and rolls off on a gear-wheel K², secured to a fixed part of the bicycle-frame and concentric to the crank-shaft B². Now when the crank-shaft 50 is rotated by the operator pressing the pedals E³ then the gear-wheel K', by rolling off on the fixed gear-wheel K², is rotated and rotates the gear-wheel K and shaft D², and thereby brings the pedals into the most advantageous 55 positions. During the downstroke the arm D³ will form an extension for the cranks C⁵, so that the thrust exerted by the rider is utilized to the fullest advantage. The gearing and the cranks C⁵ are preferably inclosed in 60 a suitable housing L, as shown in the drawings.

In the modified form illustrated in Figs. 12 to 15 the crank-shaft B³, journaled in the bicycle-frame A⁹, carries on each end a crank C⁶, in the free end of which is journaled the transversely-extending shaft D⁴, on the outer end of which is secured an arm D⁵, carrying

at its free end the pedal E⁴. On the end of the said shaft D⁴ is secured an arm D⁶ at right angles to the arm D⁵, and the said arm D⁶ is 70 pivotally connected with an eccentric-rod N, projecting from an eccentric-strap N', mounted to turn by ball-bearings on an eccentric-disk N², mounted to turn on the hub N³ of a plate N⁴, secured by flanges N⁵ to the bicycle-frame A⁹. The eccentric-disk N² is adapted to be secured on the plate N⁴ by a screw-pin N⁶, screwing in the disk N² and adapted to engage one of a series of apertures on the fixed plate N⁴. (See dotted lines, Fig. 12.) Set-screws N⁷ also fasten the hub of the plate in position. A swinging motion given to the eccentric-rod N causes the strap N' to turn on the fixed disk N² as the center. Now it will be seen that when the rider exerts a 85 downward pressure on the pedal E⁴ and the crank C⁶ swings downward then the position of the pedal E⁴ is changed relatively to the crank by the action of the eccentric-strap N' and rod N on the arm D⁵, rigidly connected 90 with the shaft D⁴, carrying the pedal E.

In order to prevent the arm D⁵ and pedal E⁴ from turning in the wrong direction at the time the crank-arm C⁶ and the arm D⁵ stand exactly at a right-angle position—that is, when 95 the crank-arm moves into a lowermost or uppermost vertical position—we provide a temporary locking device. (Shown in Figs. 12 and 15.) This locking device consists of a bolt O, fitted to slide longitudinally in the 100 crank-arm C⁶ and pressed on by a spring O' to hold the head O² of the said bolt in an outermost position. The head O² is formed with an incline O³, leading to a recess O⁴, and the said incline O³ is engaged by a roller P just 105 previous to the crank-arm C⁶ moving into a lowermost position and by a roller P' just previous to the said crank-arm moving into an uppermost position.

The rollers P P' are held diametrically opposite each other on the arm D⁵, as plainly shown in Fig. 12. Either roller P P' when passing up the incline O³ causes an inward sliding of the bolt O and a compressing of the spring O', and after the roller passes the outer 110 end of the incline it drops into the recess O⁴ at the time the crank-arm stands in a vertical lowermost or uppermost position. Thus the arm D⁵, and consequently the shaft D⁴, and the arm D⁶, carrying the pedal E⁴, are locked 115 temporarily in position to prevent the said arm D⁶ from being turned farther around in the direction it previously had. Thus the pedal E⁴ travels in the path a and the crank-arm C⁶ in the path b, both paths being indicated by dotted lines.

It is understood that by the arrangement described extended crank-arms are produced in which the extended part is always at right angles to a line drawn through the center of the eccentric-disk N² and the center of the crank-shaft B³. The angular movements of the pedal relative to the crank-arm are always controlled by the eccentric and a great lever-

age is obtained without causing the rider to move the foot through a large circle, as will be evident by comparing the paths *a* and *b*. The extension takes place only during the 5 downward stroke of the crank-arm *C*⁶, and during the upstroke the arm *D*⁵ and its pedal fold inward, as indicated in the dotted-line position, Fig. 12.

Having thus described our invention, we 10 claim as new and desire to secure by Letters Patent—

1. A bicycle-gear comprising a crank-shaft provided with cranks, a shaft journaled in the outer end of each crank, a pedal carried 15 by the said shaft, means for positively turning the said shaft to change the position of the pedal relatively to the crank and to form an extension for the latter, and a temporary locking device for the pedal, substantially as 20 shown and described.

2. A bicycle-gear, comprising a crank-shaft, a crank secured thereon, a shaft journaled in the free end of each crank, an arm on said shaft carrying a pedal, an arm extending from 25 the shaft at right angles to said shaft, an eccentric having its disk fixed to the bicycle-

frame and its eccentric-rod connected with the said shaft-arm, and a temporary locking device for the said arm, substantially as described.

3. A bicycle-gear comprising a crank-shaft provided with cranks, a shaft journaled in the free end of each crank, an arm on the outer end of the shaft, a pedal carried at the free end of said arm, an arm extending from the 35 shaft at right angles thereto, an eccentric having its disk fixed to the bicycle-frame and its eccentric-rod pivotally connected with the said arm extending at right angles to the shaft, and a temporary locking device for the said 40 arm, substantially as described.
